FOOTBALL TROPHY OR THE LIKE

Joseph Louis Je Rue, Ventura, Calif., assignor of fifty percent to John P. Lynch and Barbara J. Lynch, both of Ventura, Calif.

Filed Mar. 3, 1969, Ser. No. 15,992

Term of patent 14 years

Int. Cl. D11—02

U.S. Cl. D29—28

I claim:

The ornamental design for a football trophy or the like, substantially as shown.
